UNITED STATES PATENT OFFICE

ADOLF ZEHNDER, OF BIRKENSTORF, AND JEAN KAPPELER, OF BADEN, SWITZERLAND

BRAIDING-BOBBIN DEVICE

Application filed July 8, 1930, Serial No. 466,537, and in Switzerland July 11, 1929.

The invention relates to a thread guiding arrangement for braiding bobbins having a thread tensioning device located within a hollow bobbin carrying spindle. It is characterized by the feature that the thread guide is constructed as a fork with limbs set at an upwardly diverging angle. It is indeed known to provide a bobbin with a thread guide in the form of eyeless guide wires, but with the present construction of thread guide the thread during upward movement on the diverging fork limbs undergoes an increasing braking effect which ensures the thread leaving the bobbin tangentially.

15 The accompanying drawing illustrates by way of example an embodiment of the invention.

Figure 1 is a front view.

Figure 2 is a side view, and

20 Figure 3 is a vertical axial section with the thread being drawn off.

The bobbin α of thread having a sleeve of wood or better of paper, is carried by a hollow spindle b to which the thread guide c is secured. The latter consists of a wire fork which is coiled to grip the spindle b and has two limbs c^1, c^2 at an upwardly diverging angle, forming two separated guide paths for the thread. An eye d holds the fork limbs 30 firmly together at their lower ends and thus ensures a firm seating of the guide on the spindle b . At their upper ends the limbs are joined by a bridge e .

Within the hollow spindle b is a tension 35 spring f which is furnished at its upper end with an eye f^1 for the thread and in known manner determines the tension of the thread.

The upper end a^1 of the bobbin is provided with a guiding and braking rim for the 40 thread. Flat teeth may be formed thereon for coaction with a small pawl which may be of advantage in view of the intermittent rotation of the bobbin corresponding with the drawing off of the thread. Such teeth are 45 not essential however and will not be used with paper bobbins.

The thread α leaving the bobbin a tangentially is wound round the limbs c^1, c^2 in the manner shown in Figure 1 and passes thence 50 over the bridge e and over the upper end of

the bobbin directly to the eye f^1 of the spring f . When the thread is drawn off, in proportion as it is used, the spring f is stretched and finally the bobbin α yields to the tension in the length of thread between the eye f^1 and the bridge e , also acting as a brake, and thus rotates through a certain angle.

During the drawing off of the thread the latter moves up and down on limbs c^1, c^2 of the fork, receiving a certain degree of braking during the upward movement due to the divergence of the limbs.

Upon a breakage of the thread, the device p to which the lower end of the spring f is attached, falls into the path of a known stopping device not illustrated.

What we claim is:—

1. In braiding bobbin devices, the combination of a hollow bobbin carrying spindle, thread tensioning means located therein and 70 a forked thread-guide with limbs set at an upwardly diverging angle fastened on said spindle.

2. In braiding bobbin devices, the combination of a hollow bobbin carrying spindle, 75 thread tensioning means located therein and a forked wire thread-guide with limbs set at an upwardly diverging angle and having a coiled part seated on said spindle.

In witness whereof we have hereunto signed 80 our names this 21st day of June, 1930.

ADOLF ZEHNDER.
JEAN KAPPELER.
